CAN OR JAR OPENER

Franz K. Krag, Chicago, Ill.

Application August 13, 1932, Serial No. 628,661

3 Claims. (Cl. 81—3.1)

This invention relates to can or jar openers and has for its object providing material improvements in the ordinary types of can openers now in use, so as to simplify the operation and increase 5 the effectiveness thereof.

Of the accompanying drawing, Fig. 1 is an elevation of a can opener which embodies some of the features of my invention; Fig. 2 is an elevation of the opposite side of the opener; Fig. 3 is an edge view of the can opener; and Fig. 4 is an enlarged sectional detail view of the operative elements of the device.

Cans or jars are frequently provided with screw tops or with tops or corks that can be opened 10 more readily by rotating them relative to the jar. For the purpose of opening such jars, openers have been provided which comprise clamping means which grasp the top and hold it firmly so that it can be rotated relative to the jar. My 15 invention consists in providing improvements for such clamping means so as to increase materially the clamping force, and also to provide means for more quickly and conveniently and effectively clamping the top, especially when changing from 20 one size top to another.

The opener consists in a frame 10, which forms the guide or support for the clamping means, and also provides a handle for operating the 25 opener when the top has been clamped. I prefer to form this handle out of a U-shaped bar, and the ends of the bar are fixed relative to each other by means of the clamping member 12. However, any suitable handle may be used for the 30 purpose. The handle forms guides 13 and 14 upon which is slidably mounted the other clamping member 15. Fixed to the clamping member 15 is a plate 16 slidably mounted on the rods 13 and 14. Pivoted to the plate is a lever 17 which is 35 preferably formed of sheet material, so that flanges 18 on the end of the lever extend on opposite sides of the plate 16, and preferably a strip 19, fixed to the plate 16, is inserted to support one end of the pivot. Pivoted to the lever 17 is a 40 pawl 20 which projects between the two sheets of the handle. This pawl is adapted to coact with the rack 21 formed in one of the bars of the 45 handle.

In operation, the clamping jaws 12 and 15 are 50 pressed snugly against the sides of the cap to be removed, by shoving the plate 16 along until the cap is grasped by the jaws, with the lever 17 positioned away from the bar, as shown in Fig. 1. The lever is then pressed towards the handle 10, thus forcing the pawl 20 into coaction with the 55 rack, and, by the position of the pivots and the

arrangement of the pawl and lever, a powerful leverage is provided in the nature of a toggle-joint, so that the clamp jaws may be very firmly pressed against the cap. Thus, the friction, particularly if teeth 22 are provided in the jaws, will hold the cap so firmly that it may be readily rotated and removed from the jar.

In order to assist in manipulating quickly and effectively the apparatus, I prefer to form the pawl 20 out of sheet metal U-shaped, so that a 5 spring-like effect is produced, providing suitable friction between the pawl and lever 17. As a consequence of this arrangement, there will be no relative movement of the pawl and the lever until the lever is forced towards the handle 10, 10 and the pawl is forced into coaction with the rack. This arrangement insures the removal of the pawl from coaction with the rack whenever the lever 17 is rotated outwardly, and insures coaction of the pawl and rack whenever the 15 lever is rotated inwardly.

In addition to this mechanism, I prefer to provide a stop 25 positioned adjacent the bowed end of the handle, which limits the movement in that direction of the operating mechanism. This 25 stop is preferably provided with an outwardly projecting flange 26 upon which is formed an angular flange 27. This flange is adapted to pass under the edge of the can, or for caps which can 30 thus be removed in an ordinary manner, by using the opener as a lever, with the end 28 acting as a fulcrum on the central portion of the cap.

I claim as my invention:

1. A can opener comprising a handle having a rack thereon, a clamping jaw fixed to the handle, a second clamping jaw slidably mounted on the handle, a lever pivotally associated with the second jaw, and a pawl pivotally connected to the lever and adapted to coact with the rack to prevent separation of the jaws, the lever and pawl forming a toggle-joint connection between the second jaw and the rack, the pawl comprising a U-shaped member with its ends pivoted to the lever and resiliently pressing against the lever adjacent the pivoted point.

2. A can opener comprising a handle having a rack thereon, a clamping jaw fixed to the handle, a second clamping jaw slidably mounted on the handle, a lever pivotally associated with the second jaw, and a pawl pivotally connected to the lever and adapted to coact with the rack to prevent separation of the jaws, the lever and pawl forming a toggle-joint connection between

the second jaw and the rack, the handle comprising a U-shaped bar with the first-mentioned jaw connecting the two outer ends of the legs of the bar, and the rack being formed on the inner side of one of the bar members, the other jaw being slidably mounted on both legs of the bar and the pawl being positioned between the legs.

3. A can opener comprising a handle having a rack thereon, a clamping jaw fixed to the handle, a second clamping jaw slidably mounted on the handle, a lever pivotally associated with

the second jaw, and a pawl pivotally connected to the lever and adapted to coact with the rack to prevent separation of the jaws, the handle comprising a U-shaped bar with the first-mentioned jaw connecting the ends of the legs of the bar, the rack being formed on the inner side of one of the legs of the bar, and the outer end of the pawl when in coaction with the rack extending to adjacent the other leg.
